UNITED STATES PATENT OFFICE.

FRANK M. KINNARD, OF SEBRING, OHIO, ASSIGNOR OF ONE-HALF TO CHARLES L. SEBRING, OF SEBRING, OHIO.

STOVE-ROOM FOR POTTERIES.

1,265,091.

Specification of Letters Patent.

Patented May 7, 1918.

Application filed October 2, 1916. Serial No. 123,230.

To all whom it may concern:

Be it known that I, FRANK M. KINNARD, a citizen of the United States, residing at Sebring, in the county of Mahoning and 5 State of Ohio, have invented a new and useful Stove-Room for Potteries, of which the following is a specification.

My invention relates to drying racks and has more especial reference to what is 10 known as a "stove room", being a series of drying shelves which is used in potteries for drying the ware after the same has been molded and previous to burning the same.

In the ordinary forms of "stove rooms", 15 such as are at present in use in potteries the drying racks are generally stationary within an inclosed room, aisles being left between each tier of shelves to permit the workmen to pass between the racks or frames when 20 placing the green articles from the molds upon said shelves or in removing the dried articles therefrom. A series of steam pipes are located upon the floor of the "stove room" maintaining an even temperature of 25 from 110° to 120° F. within the "stove room" constantly. With this form of "stove room" it is necessary in filling or emptying the frames for the men to work in the "stove room" and the extremely high temperature 30 of the room makes it impossible for a man to stay on the job longer than an hour at a time. In constructing the above described form of stove room it is necessary to space each rack of shelves sufficiently from the adjacent racks to allow the men to pass through 35 the aisles between the racks and this construction necessitates the utilization of considerable floor space.

The object of my invention is to provide 40 a stove room which comprises sufficient shelf space to hold an entire day's output of one workman, considerably less floor space being used than in the present form of stove room.

45 A further object is to provide a stove room of the character mentioned upon which the ware may be thoroughly dried without necessitating the use of a series of steam pipes or their equivalents beneath the drier racks.

A still further object is the provision of 50 a stove room of the character referred to in which the temperature of the room is kept slightly above normal, but moderate

enough to allow the men to work therein 55 without any great hardship.

A still further object is to provide a stove room of the character mentioned in which it is not necessary to inclose the drying racks in a separate room from the room in which 60 the molding is done.

My improved form of stove room comprises a drying device arranged to be located within the room in which the molding is done. With this construction no steam pipes 65 are used beneath the drying racks as in the form of stove rooms at present in use, it being merely necessary to maintain the temperature of the room in which the device is located slightly above normal, the temperature being sufficiently moderate to allow 70 the men to work in the room without putting any hardship upon them. My construction comprises stationary end sections which are provided with shelves, a series of tracks connecting said end sections at their upper extremities. A series of movable sections are slidably mounted upon said tracks by means of pulleys on the like, each of said movable sections comprising two spaced tiers of 80 shelves which may be moved into position to allow the men to pass before the particular rack which is being filled or emptied, the device being so constructed that when 85 all the shelves are filled the movable sections may be spaced from each other and from the stationary end sections sufficiently to allow a complete circulation of air around all sides of the molds carrying the green ware. The entire device, constructed as 90 above briefly pointed out, may be placed within considerably less floor space than is required for the present form of stove rooms. Each stove room comprises sufficient 95 shelf space to hold an entire day's output of one man and the ware is sufficiently dried over night to be removed in the morning, allowing the same to be refilled each day.

With these objects in view the invention consists in the novel construction and arrangement of parts, hereinafter described, illustrated in the accompanying drawings, and particularly pointed out in the appended claims, it being understood that various changes in the form, proportions, size, and minor details of construction may be made within the scope of the appended claims, without departing from the spirit

or sacrificing any of the advantages of the invention.

In the drawings:

Figure 1 is a side elevation of a device 5 constructed in accordance with my invention, the movable sections being placed in position to allow a workman to fill or empty one of the stationary end sections and the near side of the adjacent movable section, 10 said movable section being also shown in dotted lines in the position in which it is placed after being filled in order to fill the next adjacent movable section.

Fig. 2 is a side elevation of the device, 15 showing the movable sections in the position in which they are placed after being filled in order to allow circulation of air around all of the molds for the purpose of drying the ware.

Fig. 3 is a section on the line 3—3, Fig. 1.

Fig. 4 is an enlarged fragmentary sectional view through one of the movable sections.

Similar numerals of reference indicate 25 corresponding parts throughout the several figures of the drawings.

Referring more especially to the construction illustrated in the accompanying drawings, the numerals 1—1, indicate the standards 30 upon which the device is supported, these standards being four in number and located at the four corners of the stove room. A transversely disposed I-beam 2 connects each end pair of the standards 1, at their 35 upper extremities and superimposed upon said I-beams is a plurality of tracks 3. Spaced shelves 4 are provided between each pair of the standards 1 thus forming a stationary rack or tier of shelves at each extremity of the device.

A plurality of movable racks are supported from the tracks 3, these racks being designated by the letters *a*, *b*, *c* and *d*. The construction of each of these movable racks 45 is the same, each rack being preferably composed of two spaced tiers of shelves *e* and *f*, each tier of shelves comprising the vertical end members 5 connected together by suitable tie rods 6 and carrying therebetween 50 a series of shelves 7. Each series *e* and *f* is spaced apart at their upper and lower extremities by means of blocks 8.

Brackets 9 are provided at the upper extremity of each of the movable racks, said 55 brackets carrying traveling wheels 10 which are mounted upon tracks 3. Each of the movable racks is provided upon each side, at its upper and lower extremities with blocks 11, said blocks being arranged to 60 contact with each other and with the blocks 12 carried by the stationary end sections when the racks are moved together as shown in Fig. 1 of the drawings, these spacing blocks being for the purpose of properly spacing 65 the shelves of adjacent racks in order to

allow a circulation of air between the molds carried upon said shelves.

The molds 13 upon which the green ware 14 is carried are each provided upon their under surface with a chamber 15 and each of the shelves 7 is of less width than the diameter of said chamber, thus allowing a circulation of air entirely around the mold in order to more quickly dry the ware, the sections *e* and *f* of each of the movable racks 75 being spaced apart by means of the blocks 8 space the molds 13, upon adjacent shelves, allowing a circulation of air between the molds.

When it is desired to fill the stove room 80 the racks *a*, *b*, *c* and *d* are moved together as shown in Fig. 1 of the drawings and the tier of shelves *e* of the section *a* as well as the shelves in the adjacent stationary rack are filled first, the workmen having sufficient room to pass between said racks after 85 which the rack *a* is moved into the position shown in dotted lines in Fig. 1, the tier of shelves *f* of said rack and the tier *e* of the rack *b* being next filled, the rack *b* being 90 then moved into contact with the rack *a*. This operation is repeated until all of the racks are filled with the ware, after which 95 the racks are separated as shown in Fig. 2 in order to allow the air to circulate freely around all molds in each rack for the purpose of drying the ware.

Each of the stove rooms as above described comprises sufficient shelf space to accommodate an entire day's output of one 100 molder and the ware is sufficiently dried over night to be removed in the morning allowing the stove room to be refilled each day as the articles are molded. For the convenience of the workman rods 16 are provided upon the end members of the racks for 105 the purpose of receiving portable shelves which may be placed upon said rods when the dried ware is being removed from the racks and as each of the portable shelves is 110 filled with ware it is removed from the stove room to be burned.

Although the drawings and above specification disclose the best mode in which I have contemplated embodying my invention 115 I desire to be not limited to the details of such disclosure, for, in the further practical application of my invention, many changes in form and construction may be made, as circumstances require or experience suggests, without departing from the spirit of 120 the invention, within the scope of the appended claims.

I claim:

1. A stove room of the character described 125 comprising a pair of stationary, spaced end racks, shelves mounted in said racks, tracks connecting said racks at their upper extremities, movable racks suspended from said tracks, each of said movable racks compris- 130

- ing a pair of spaced tiers of shelves, said shelves arranged to receive molds having chambers in their lower sides, each of said shelves being of less width than the diameters of said chambers and spacing blocks mounted upon each of said racks. 5
2. In a drying rack for potteries comprising a pair of stationary end racks, shelves mounted in said racks, tracks connecting said racks at their upper extremities, pairs of co-joined relatively spaced movable racks suspended from said tracks, 10
- tiers of shelves upon each of said racks, the said shelves being designed to receive molds of greater diameter than the width of said shelves, spacing blocks upon the opposite sides of each of said co-joined pairs of racks, said spacing blocks being adapted to hold said movable racks apart to permit the circulation of air therebetween. 15
- 20
- In testimony that I claim the above, I have hereunto subscribed my name.

FRANK M. KINNARD.
